UNITED STATES PATENT OFFICE.

BENJAMIN FRANKLIN NIXON, OF WINNIPEG, MANITOBA, CANADA.

SHIPWRECK SIGNAL-INDICATOR.

1,137,782.

Specification of Letters Patent.

Patented May 4, 1915.

Application filed May 7, 1914. Serial No. 337,041.

To all whom it may concern:

Be it known that I, BENJAMIN F. NIXON, a citizen of the United States of America, residing at Winnipeg, in the Province of Manitoba and Dominion of Canada, have invented certain new and useful Improvements in Shipwreck Signal-Indicators, of which the following is a specification, reference being had therein to the accompanying drawing.

This invention relates to a ship wreck signal indicator and has for its principal object the production of a device which is adapted to be normally carried upon the upper deck 15 of a ship which is adapted to float therefrom provided the ship sinks, whereby the buoy may remain upon the surface of the water so as to indicate the spot or position where the ship rests after sinking.

Another object of this invention is the production of a device which is provided with a cable for attaching the same to the deck of a ship whereby the cable may be paid so as to allow the indicator to remain 25 upon the surface of the water while the ship sinks and thus indicate the spot or position where the ship may be found.

Another object of this invention is the production of a device adapted to facilitate 30 the location of a ship which has sunk, the ship and indicator being provided with simple and efficient means for relieving the cable of the strain caused by a sudden jerk and thus preventing the cable from being 35 severed.

A still further object of this invention is the production of a device having a framework having a plurality of lights for facilitating the location of the buoy and also a 40 plurality of bells for attracting attention to the same, this buoy being adapted to be attached to the body of a vessel.

With these and other objects in view this invention consists of certain novel combinations, constructions, and arrangements of parts as will be hereinafter fully described 45 and claimed.

In the accompanying drawings like characters of reference indicate like parts in the 50 several views, wherein:—

Figure 1 is a perspective view of the shipwreck signal indicator illustrating the same in use and the manner in which the same is adapted to drift above a vessel which has 55 been disabled and sunk. Fig. 2 is a central vertical section taken through the ship

wreck signal indicator. Fig. 3 is a section taken on the line 3—3 of Fig. 2 looking in direction of the arrows. Fig. 4 is a fragmentary detailed perspective view of the 60 supporting means for the device which is carried by the ship and also of the retaining means. Fig. 5 is a section taken on the line 65 5—5 of Fig. 2 looking in direction of the arrows. Fig. 6 is a section taken on the line 6—6 of Fig. 2. Fig. 7 is a section taken on the line 7—7 of Fig. 2. Fig. 8 is a vertical section through the retaining means carried by the ship. Fig. 9 is a diagrammatic view of a certain automatic switch used in connection with this invention.

Referring to the accompanying drawings by numerals 1 designates the body of the buoy which converges toward its lower portion as disclosed at 2 and in which the 75 ballast 3 which is formed of lead or any other suitable material is carried. The upper portion of this body 1 is closed by the cap 4 which is secured in place by rivets 5 and which may then be suitably sealed. By 80 forming the buoy in this manner it will be seen that the same will be provided with a floating body which is formed to carry a ballast for always retaining the same in its correct upright position. Pins 5 extend 85 from the sides of the body 1 so as to pass through the body 1 and the cap 4 and upon these pins there is secured a bowed strip 6. This bowed strip 6 is formed so as to allow the central portion of the same to be placed 90 at a spaced distance above the upper portion of the cap 4 and this strip is held in pivotal movement on the pin 5 by means of a staff 7 which has its lower end carried within the annular rib 8 formed upon the cap 4. This 95 staff 7 passes for a spaced distance above the strip 6 and is adapted to carry at its upper end flags 9. One of these flags being adapted to indicate the point to which the ship is sailing and the other to indicate the place 100 from which the ship came. This strip 6 also carries a number of bells 10 which depend from the under surface of the strip and are positioned between the strip and the cap 4. These bells are allowed to swing so 105 that the action of the water upon the buoy will cause the bells to ring as the buoy swings to and fro and rides the waves. The strip 6 also carries upon its upper surface a number of electric lights 11 which are provided with the shielding screen 12. These lights 11 are electrically connected by means 110

of the wires 13 and 14 to the batteries 15. The batteries 15 are carried within the box 16 formed upon the cap 4. In this manner it will be seen that the buoy is also provided with lights for allowing the same to be easily located during a fog or during the night independent of the bells 10. It is to be noted, however, that when the buoy is normally carried upon the deck of a ship 10 the bells may be muffled in any suitable manner while the lamps may be disconnected so that the bells will not ring and the lights will not be lighted when the device is not in use. This buoy is adapted to be attached 15 to the deck of a vessel and therefore there is provided a suitable means, which will be hereafter described for supporting a cable and attaching the cable to the buoy. There is provided a sleeve 15 which is secured by 20 the rivets 16 to the central portion of the body 1. This sleeve 15 is provided at its lower portions with a pair of plates 17 and 18 which have annular flanges 19 for allowing the securing means to be passed therethrough for fixedly retaining these plates in the lower portion of the sleeve 15. It is, 25 of course, obvious that the plates are secured within the sleeve 15 and the sleeve is secured to the body 1 so as to prevent the 30 passage of water therebetween, owing to the snug construction of the several parts and after which the application of any suitable material may be placed around the junctions or cracks for efficiently sealing the same; 35 between the plates 17 and 18 there are carried the vertical rods 20 and 21. The block 22 is slidably mounted upon the rods 21 and is normally held adjacent the plate 18 by means of the coiled spring 23 which is positioned 40 between the rods 21 and bears at one end upon the plate 17 and at the opposite end upon the sliding block 22. This block 22 has the guide fingers 24 extending from each end and these guide fingers are adapted 45 to have eyes 25 which fit upon the vertical rods 20. The links 26 are secured at their upper ends to the fingers 24 and depend or pass through the plate 17. The 50 lower ends of these links 26 carry the bracket 27 having the depending arms 28. The drum 29 is pivotally secured to these depending arms 28 and upon this drum the cable 30 is carried. One end of the drum 29 is provided with a ratchet sheet 31 which is 55 engaged by the pawl 32 carried by the bracket 27. This pawl engages the ratchet wheel 31 for preventing the drum 29 from rotating in one direction but is positioned so as to allow the drum to rotate so as to 60 allow the cable to be unwound or paid.

From the foregoing description it will be seen that the device carried by the buoy will efficiently support the cable 30 and will allow the same to be unreeled therethrough as 65 a ship sinks. If, however, the cable unreels

to the end or a sudden jerk is imparted thereto the links 26 will draw downwardly upon the fingers 24 thereby compressing the spring 23. In this manner the yieldable connection will take up the sudden strain and will prevent the cable 30 from being broken or severed. 70

The upper deck 33 of the ship 34 is provided with the vertical arms 35 having the Y-shaped branch 36 formed integral upon each arm 35. When the buoy is carried upon the deck of a ship under normal conditions, the pins 5 will be carried by the branches 36 of the arms 35 and be held in its correct position. When, however, the ship begins to sink the buoy will be floated by the water from engagement with the arms 35 and will thereby be lifted from engagement with the ship and will begin to float. The deck 33 is also provided with the rods 37 having nuts 38 carried upon their upper ends for retaining the bearing plate 39 thereon. This bearing plate is provided with a pocket 40 for receiving one end of the coiled spring 41. The lower end of the coiled spring rests in the socket 42 formed in the plate 43 from which the projections 44 extend so as to slidably support the plate 43 upon the rods 37. An eye 45 is secured to the plate 43 and to this eye there is attached the lower end of the cable 30. This cable passes upwardly through the coiled spring 41 and through the opening 46 formed in the bearing plate 39, so as to always provide a yieldable connection for the lower end of the cable whereby the sudden strains upon the cable will be relieved by the spring 41 as well as by the spring 23. It will also be seen that the cap 4 may be provided with a plurality of boxes 16' which are similar to the battery box 16. Each box 16' has its body portion formed integral upon the cap 4 and is provided with a hinged collar 47 which may be held in a closed position by any suitable locking means 110 48. These boxes are adapted to contain articles such as the passenger list, the cargo list, and the dates of each date so that the time when the ship sunk will be determined. It will also be noted that the placing of the 115 bells below the lamps which are carried by the strips 6 will prevent the bells from striking the lamps and breaking the same as the buoy moves.

From the foregoing description it will be 120 seen that a ship wreck signal indicator has been produced which is so formed as to be easily carried by the upper deck of a ship but which is adapted to easily drift therefrom as the ship sinks and remain upon the 125 surface of the water and to be attached to the ship by a cable so as to determine the exact location of the ship. Furthermore, this device is provided with simple and efficient signaling means for drawing attention 130

thereto and means for yieldable connecting the cable and thus preventing the cable from being broken or severed due to undue strain being brought to bear thereon.

5 By referring to Figs. 1 and 9 it will be seen that an automatic switch has been produced whereby a circuit may be automatically closed for illuminating the electric lights. The cap 4 carries a pivot-blade 49 having a cord 50 connected thereto. This cord passes through a series of guide-eyes 51 and is attached at its opposite end to a metallic ball 52. This ball 52 rests in a shallow bowl 53 when the buoy is in its correct position upon the deck of a ship. 10 When however the ship sinks and the buoy begins to float, the rocking of the buoy by the waves will cause the metallic ball 52 to be thrown from engagement with the bowl 53. The weight of this metallic ball will draw upon the cord 50 thereby drawing the cord through the eyes 51 and swing the blade 49. This action of the blade 49 will cause the same to be swung over the contact 15 points 54 of the conductors 13 and 14 thereby forming a circuit for lighting the electric lamps. It is obvious that when this buoy is in its correct position upon the deck of a ship, the metallic ball 52 will remain in the 20 bowl 53 thereby causing the circuit to remain broken.

It is of course obvious that the cable 30 may be provided with numerals at spaced distances apart to facilitate the determining 35 of the depth of the water in which the ship is sunk.

I claim:—

1. A device of the class described comprising a body converging toward its lower end, 40 a cap fixed upon the upper portion of said body, a ballast member positioned within the lower portion of said body whereby said body will be held in its correct vertical position, signaling means carried above 45 said cap, whereby said signaling means will be held above the water, and means yieldably connecting a cable to the lower portion of said body, said cable adapted to be connected to a vessel whereby when 50 a vessel sinks said body may float and allow said cable to engage a vessel whereby the location of the vessel may be determined, and said yieldable means adapted to prevent the breaking of said cable.

55 2. A device of the class described comprising a hollow body, said body converging toward its lower portion, a cap carried upon the upper portion of said body for forming a closure therefor, a sleeve fixedly secured 60 to the lower portion of said body, plates fixedly secured within the lower portion of said sleeve, means connected to said plates for yieldably attaching a cable to said plates, said cable adapted to be attached also to a 65 vessel, said means adapted to unreel said

cable as a vessel sinks whereby said body will float to indicate the position of a vessel.

3. A device of the class described comprising a hollow body, a cap carried by the upper portion of said body forming a closure for the same, signaling means carried above said cap, a sleeve fixedly secured upon the lower portion of said body, plates fixedly secured within said sleeve and at a spaced distance apart, a plurality of vertical rods fixedly secured between said plates, a sliding plate carried upon a pair of said vertical rods, a spring bearing upon one of said fixed plates and upon said sliding plate will be normally urged in one direction, and means connected to said sliding plate for securing a cable, said cable adapted to be secured to a vessel whereby said cable may be attached to a vessel so as to allow the body to indicate the position of a vessel, said spring and sliding plate being adapted to yieldably connect the cable thereby preventing the same from being broken by undue strain being brought thereon.

4. A device of the class described comprising a supporting body, said body converging toward its lower portion, a cap for closing the upper portion of said body, a signal, and means carried above said cap, said signaling means adapted to attract attention to said body, a sleeve carried upon said body, a plurality of spaced plates fixedly secured within said sleeve, vertical rods carried by said plates, a sliding plate positioned upon a pair of said rods, a screen carried between said last-mentioned rods and bearing upon said sliding plate for normally urging said sliding plate in one direction, a finger having an eye extending from each end of said sliding plate and engaging the remaining vertical rods, links connected to said finger and extending through one of said fixed plates, a bracket carried upon the outer ends of said links, whereby said bracket will be yieldably supported, a drum carried by said bracket, a cable secured to said drum, said cable adapted to be also attached to a vessel, said drum adapted to rotate for allowing the cable to unwind whereby when a vessel sinks a cable will remain attached thereto and the body will float so as to indicate the location of the vessel, said spring adapted to take up any undue strain adapted to bear upon the cable and thus preventing the same from being broken.

5. A device of the class described comprising a floating body, a cap forming a closure for the upper portion of said body, signaling means positioned above said cap, a sleeve carried upon the lower portion of said body, a plurality of fixed plates carried within said sleeve, vertical rods carried by said fixed plates, a sliding plate carried by a pair of said rods, a spring bearing upon said slid-

ing plate for normally urging the same in one direction, a finger extending from each end of said sliding plate and engaging one of said vertical rods, links engaging said fingers and extending through one of said fixed plates, a cable, means for supporting said cable upon said links, said cable adapted to be secured to a vessel whereby said cable may be paid out so as to allow the body to float and thus indicate the location of a vessel.

6. A device of the class described comprising a body, a cap carried by the upper portion of said body and forming a closure therefor, a plurality of pins extending from said body for normally forming a support for said body, a bowed strip carried upon said pins, the central portion of said strip being positioned at a spaced distance above said cap, a plurality of bells carried upon the lower portion of said strip, said bells being adapted to ring as said body moves, a plurality of lights carried upon the upper portion of said strip, retaining receptacles carried by said cap, and means formed upon the lower portion of said body for connecting same in engagement with a vessel whereby the body may float to indicate the location of a vessel.

7. In a device of the class described the combination with a vessel, arms extending from said vessel and terminating in branches at their upper ends, of a hollow body, said body provided with a closure cap, pins ex-

tending from said body, said pins adapted to be carried by said vertical arms, whereby said body may be supported upon a vessel, a cable secured to said body and to said vessel, means for yieldably connecting the cable at each end whereby said body may float for indicating the location of a vessel, and said yielding means adapted to prevent the undue strain upon said cable.

8. In a device of the class described the combination with a vessel, vertical arms terminating in branches at their upper ends carried by said vessel, rods carried by said vessel, a bearing plate secured to the upper portions of said rods, a sliding plate positioned upon said rods, a spring bearing upon said plates, a hollow body, pins extending from said hollow body and adapted to engage said arms whereby the same may be normally supported, and a cable connected to said sliding plate at one end and to said hollow body at the opposite end whereby said cable may be paid out so as to connect the body to said vessel for allowing said body to indicate the location of a vessel, and said spring being adapted to relieve undue strain upon said cable.

In testimony whereof I hereunto affix my signature in presence of two witnesses.

BENJAMIN FRANKLIN NIXON.
